UNITED STATES PATENT OFFICE.

EDWARD CRAIG, OF ST. JOSEPH, MICHIGAN.

PRINTING-PRESS AND BLANKING-MACHINE.

1,383,531.

Specification of Letters Patent. Patented July 5, 1921.

Application filed September 30, 1916. Serial No. 122,964.

To all whom it may concern:

Be it known that I, EDWARD CRAIG, a citizen of the United States of America, and resident of St. Joseph, Berrien county, Michigan, have invented a certain new and useful Improvement in Printing-Presses and Blanking-Machines, of which the following is a specification.

My invention relates to feed-mechanism in general, but more particularly to mechanism of this kind for feeding sheet material from a printing press to a blanking press, so that the required printing is done before the blank is cut from the traveling sheet.

Generally stated, the object of my invention is to provide an improved feed-mechanism which will accurately feed the sheet material, periodically or intermittently, and which can be adjusted to vary the extent of the feeding motion.

It is also an object to provide certain details and features of construction and combinations tending to increase the general efficiency and desirability of a feed mechanism of this particular character.

To the foregoing and other useful ends, my invention consists in matters hereinafter set forth and claimed.

In the accompanying drawings:—

Figure 1 is a side elevation of a machine for printing and blanking sheet material, having feed-mechanism for feeding the sheet material from the printing press to the blanking press, involving the principles of my invention.

Fig. 2 is an enlarged detail sectional view of a portion of said feed-mechanism, this figure being a section on line 2—2 in Fig. 3.

Fig. 3 is a plan of the mechanism shown in Fig. 2.

Fig. 4 is an enlarged detail horizontal section on line 4—4 in Fig. 2.

Fig. 5 is a section on line 5—5 in Fig. 3.

As thus illustrated, the machine comprises a printing press A, of any suitable character, and a blanking press B, of any suitable, known or approved construction. The two presses are preferably mounted on a base C, in such position that the sheet material may be fed from the printing roll *a* of the printing press to the blanking press. Thus the sheet material is operated upon by the printing press before it reaches the blanking press, and before the blanks are cut.

The feed-mechanism for feeding the sheet material from the printing press to the

blanking press is as follows: A horizontal frame D incloses the printing press and is provided with transverse bars 1 and 2 disposed in front and rear of said printing press. Square shafts 3 and 4 extend transversely of said frame, adjacent said bars, and are each provided with a plurality of forwardly extending arms 5 having hammer-heads 6 to bear down upon the sheet material, thus clamping the latter tightly against said bars 1 and 2, when it is desired to hold the sheet stationary for the blanking operation. These shafts are provided with short vertical arms 7, both above and below, which are connected from one shaft to the other through the medium of the upper and lower rods 8 and 9, whereby when one shaft is rocked the other shaft will also be rocked in unison therewith. It will be understood that the end portions of these shafts are made round to turn in suitable bearings secured to the frame D, whereby each shaft extends transversely of the machine and is supported at its ends. The hammer-heads 6 are secured to the lower ends of the vertical screws 10 which are adjustably mounted in the ends of the arms 5, so that these heads may be raised and lowered to accurately adjust them in relation to the cross-bars 1 and 2, thereby to clamp the paper exactly in the required manner. The shaft 4 is also provided with a forwardly extending arm 11 which is provided with a roller 12 and is mounted to turn about a horizontal transverse axis. Between the shaft 4 and the blanking press B, the upper and lower shafts E and F are mounted to turn in suitable bearings on the frame D, being arranged transversely of the machine. The upper shaft E is provided with a plurality of feed-disks *e* of suitable thickness to bear upon the upper surface of the sheet material, and which are spaced apart in any suitable manner. The lower shaft F is provided with larger feed-disks *f* which bear against the end surface of the sheet material, directly below the disks *e*, so that in effect co-operating feed rolls are provided to feed the sheet material forward. The disks *f* are, however, each preferably composed of two sections, the section 13 being disk-like in form and secured to the hub 14 which is keyed to the shaft F in any suitable manner. The section 15 is also disk-like in shape, but is secured to the gear-wheel 16 which is loosely mounted on the

hub-portion 17 and held thereon by the screw-threaded ring 18, whereby the section 15 is free to rotate relative to the section 13, the two sections being held flatwise together. 5 The section 13 of each lower feed-disk is provided with a round opening 19 for the shaft 20, which latter extends parallel with the shaft F, but the section 15 is provided with curved slots 21 through which the shaft 20 extends. Thus the shaft 20 has a fixed 10 relation to the section 13, being adapted to rotate in the openings 19, but the section 15 can turn relative to said shaft, this movement being limited by the length of the slots 15 21, as the ends of this slot will engage said shaft when the section 15 is turned in either direction. The shaft 20 is provided with pinions 22 for engaging the gear-wheel 16, and for thereby rotating the latter, thus 15 relatively rotating the two sections of each feed-disk. This relative rotation, it will be seen, is for the purpose of changing the relation between the peripheral engaging portions 23 of the section 15 and 24 of the section 13, thus in effect lengthening or shortening the extent of contact which each feed-disk has with the under side of the sheet material. These portions 23 and 24 are formed on a greater diameter than the remaining portions 20 of the periphery of the feed-disk, so that the feeding motion of the sheet material commences when the portion 24 engages the under side of the sheet. The feeding motion continues until the portion 23 passes 25 out of engagement with the under side of the sheet, so that the feeding motion continues for only a fraction of the rotation of the feed-disks. By rotating the shaft 20, the extent of feed can be varied to suit the 30 requirements and to insure accuracy in the general operation of the entire machine. The roller 12 rests upon one of the feed-disks f, preferably the outermost disk, and it is moved up and down by the periphery 35 of said disk, being raised when it engages the portion 24 of the disk and lowered when it is disengaged from the portion 23 of the disk, whereby the disk surface has a cam for 40 rocking the shaft 4, thus causing the hammer-heads 6 to move up and down. The construction is such, and the operation of the different parts is so timed, that the hammer-heads 6 press down on the sheet material at the moment when the under surface 45 of the sheet is disengaged by the portions 23 of the feed-disks, so that the sheet is positively held stationary as soon as the sheet is disengaged by the feed-mechanism. This 50 prevents over-feeding of the sheet material, and insures accuracy in the operation of the machine. While the sheet is being fed forward, the printing press is operating on the sheet. Any suitable means can be employed 55 for operating the printing press. This is 60 preferably accomplished by a train of gears

25, 26, 27, 28 and 29, the latter having its axis coincident with the axis of the lower roll of the printing press, and the gear 25 being mounted on the shaft F and keyed thereto. These gear-wheels are so proportioned that the rolls of the printing press 70 operate at the required speed to feed the sheet material.

The operation of the machine is as follows: The feed-disks f are operated at a constant speed by the gearing, but during the operation of the blanking press B the sheet material is held stationary by the hammer-heads 6, and at this time the disks f are not in engagement with the under side of the sheet. While the sheet is thus standing still, the printing press, of course, is, by reason of any suitable or well-known provision for that purpose, not in operative relation to the sheet, and is not printing thereon. As 80 soon as the blanking press B has cut out a blank, the hammer-heads 6 are automatically lifted, and the feed-disks f engage the under surface of the sheet, thus again feeding the latter forward, at which time the printing press is printing on the sheet material. During this operation of the printing press A, the blanking press B is not operating on the sheet material.

The blanking press B has a lower operating shaft b which is connected by the gears 30, 31 and 32 with the gear 25 on the shaft F, whereby the latter is the medium of power-transmitting connection between the blanking press and the printing press. The shaft b is rotated by the large gear-wheel 33 which is keyed thereon and which engages a pinion 34 on the drive-shaft 35, the latter having a belt-pulley 36 for operating the machine.

The idlers 26 and 27 are mounted on the curved supporting arms G, which latter has one end supported on the shaft F, and the other end on the shaft or journal g for the idler 28, which latter operates the printing press. The idlers 31 and 32 are mounted on the frame D in any suitable or desired manner. With this arrangement, the printing press is operated by a train of gears extending from the blanking press, and the feed-mechanism is operated by one of the intermediate gears.

The printing press A has its roll a provided with the ordinary rubber blanket, wrapped around the surface of the roll for a portion of the circumference thereon, so that the uncovered surface of the roll is out of contact with the sheet material. In this way, the printing press only feeds the paper and operates thereon during the time that the portions 23 and 24 of the feed-disks are in engagement with the under surface of the sheet material. Consequently, when the feed-rolls or disks e and f release the sheet, the rolls of the printing press simultaneously do 125 130

- the same thing, and it is at this time that the hammer-heads 6 instantly clamp the sheet to the table of the machine, so that the momentum will not carry the sheet forward.
- 5 The two rolls H and I of the printing press imprint different colors on the printing surface of the roll a, in the usual and well-known manner, thereby to produce the two-color effect. A printing press of this kind
- 10 involves, therefore, first, a printing operation on the surface of the roll a, and a transferring of the impressions from this roll to the upper surface of the sheet material, so that the two-color effect is produced without the necessity of running the sheet through the press more than once, or through more than one press. As shown, the diameter of the roll a is substantially the same as the diameter of the feed-disks or
- 15 rolls f, so that the extent of contact of the roll a with the upper side of the paper is always the same as the extent of contact of said disks with the under side of the sheet, whereby the feed-mechanism comprising the
- 20 rolls e and f will always start to feed the sheet forward at the exact instant that the printing press commences to feed the sheet forward. Also, the feed-mechanism will then always release the sheet at the same
- 25 time that the latter is released by the rolls of the printing press. The printing press shown is a well-known form, it being what is ordinarily known as an offset press (the colors being printed on the printing roll and
- 30 then offset from this roll to the surface of the sheet material), but I do not limit myself to any particular construction, and any suitable or desired form of press may be used which will serve the purpose.
- 35 40 It will be seen, therefore, that in one case the roll f is used as a feed roll, coöperating with the upper rolls e for this purpose, whereas in another instance a roll f forms a cam for engaging the roller 12 on the arm
- 45 50 55 60 65 70 75 80 85 90 95 100 105 110 115 120 125 130
- 11 and controls the two rock shafts 4 upon which are mounted the arms 5 that carry the means 6 and 10 for engaging the sheet. In either case, however, the roll is formed by a plurality of sections arranged flatwise together on the shaft F, each section having an extended edge portion, and these extended edge portions combining to form a peripheral elevation on the roll, the extent of which elevation is variable circumferentially of the roll by relative adjustment of the sections, in the manner explained. In one case this peripheral elevation serves as a cam for variably controlling the arm 11, and in the other case it serves in coöperation with the feed rolls e to variably feed the sheet.
- 76 What I claim as my invention is:—
1. A machine having means for operating upon and for feeding sheet material, comprising a plurality of rotary feeding mem-
- bers to engage the surface of the sheet material, each member comprising relatively adjustable sections to vary the length of the contact with the sheet material, thereby to cause the sheet to move forward either a greater or a lesser distance, a shaft on which said members are spaced apart, and mechanism to simultaneously adjust all of said members.
2. The structure specified in claim 1, said mechanism comprising a gear-wheel secured to one section of each member, a shaft, and a pinion on said shaft to engage each gear-wheel.
3. The structure specified in claim 1, one section of each member having a curved slot, the other section having a round opening, said mechanism comprising a shaft extending through said round opening, a gear-wheel rigid with each section having the slot, and a pinion on said shaft to engage each gear-wheel.
4. The structure specified in claim 1, each section having a peripheral engaging portion extending for less than the circumference of said rotary member, one engaging portion following the other, with the front end of one portion and the rear end of the other portion a distance apart to give the required extent of feed-movement.
5. The structure specified in claim 1, each section having a peripheral engaging portion extending for less than the circumference of said rotary member, one engaging portion following the other, with the front end of one portion and the rear end of the other portion a distance apart to give the required extent of feed-movement, and said mechanism serving to rotate the sections relatively to each other to change said distance.
6. The structure specified in claim 1, one section of each member having a curved slot, said mechanism comprising a shaft carried by the other section of each member and passing through the slot of each member, gear-wheels rigid with the sections having said slots, and pinions on said last mentioned shaft to engage said gear-wheels, each section having an engaging portion, and rotation of said pinions and gear-wheels causing relative rotation between the two sections of each member to vary the distance between the front end of the engaging portion of one section and the rear end of the engaging portion of the other section of each member.
7. A machine having means for operating upon and for feeding sheet material, comprising supports for the sheet material, rock-shafts above said supports, hammer-heads carried by said rock-shafts to bear down upon the sheet material, connections between the two shafts to cause said hammer-heads to operate in unison, feed mecha-

nism comprising rotary members to engage the sheet material and feed the same forward, said members having intermittent engagement with the sheet, and means operated by said mechanism to positively lift said hammer-heads simultaneously with the commencement of the forward feeding motion of the sheet.

8. The structure specified in claim 7, a feed shaft for said rotary members, a printing press arranged to operate on the sheet material at a point between the two rock-shafts, means to operate said feed shaft, and a power-transmitting connection between the feed shaft and the printing press.

9. The structure specified in claim 7, a printing press arranged to operate on said sheet at a point between the two rock-shafts, a feed shaft for said rotary members, means to continuously operate said feed shaft, and a continuously operating power-transmitting connection between said feed shaft and the printing press.

10. A machine having means for operating upon and for feeding sheet material, comprising a plurality of rotary feed-members to engage the surface of the sheet material, said members having peripheral engaging portions which do not extend for the full circumference thereof, thereby to enable each member to operate for a portion of each complete rotation without engaging the sheet material, a device to hold the sheet material stationary during the inoperative portion of the rotation of said member, and means operated by one of said members to control said device.

11. The structure specified in claim 10, each member comprising two relatively movable sections, each section carrying a part of said engaging portion, so that relative movement between the two sections causes a lengthening or shortening of said portion, thereby to lengthen or shorten the feeding movement, and causing a corresponding variation in the operation of said device.

12. The structure specified in claim 10, said device including a hammer-head to bear upon the sheet, and said means comprising an arm provided with a roller to engage the periphery of said one member.

13. In a machine of the class described, the combination of mechanism for feeding a sheet of material horizontally, a rock shaft extending transversely above the path of

travel of the sheet, an arm extending horizontally from said rock shaft, means on said arm to engage the sheet, thereby to hold the sheet stationary, a rotary cam, and a connection between said cam and said rock shaft, so that the sheet is released by the raising of said arm when the shaft is rocked by said cam.

14. A structure as specified in claim 13, said arm extending in the direction of travel of the sheet, and said means for engaging the sheet comprising a vertically disposed screw having its lower end provided with a head.

15. A structure as specified in claim 13, in combination with another rock shaft disposed a distance from said first mentioned rock shaft, a printing press between the two rock shafts, an arm mounted on the second rock shaft and provided with means to engage the sheet, and a connection between the two rock shafts, whereby both rock shafts are oscillated in unison by said cam.

16. In a machine of the class described, the combination of a plurality of cam sections disposed flatwise together, a shaft upon which the sections are mounted to rotate in unison, so that in effect the sections form a single cam, a pinion mounted on one section to rotate about an axis parallel with said shaft, gear teeth rigid with another section and arranged to engage said pinion, means for rotating said pinion to change the relation between the sections of the cam, and means for engaging said cam and subject to variable operation thereby in accordance with the adjustment thereof.

17. In a machine of the class described, the combination of a plurality of feed roll sections disposed flatwise together, a shaft on which the sections are mounted to rotate in unison, so that the sections constitute a single feed roll, each section having an extended edge for a portion of its circumference, a pinion mounted on one section, gear teeth rigid with another section to engage said pinion to change the relation between the different sections, so that the extended edges of the sections will combine to form a peripheral elevation of greater or less extent circumferentially of the feed roll, and means cooperating with said peripheral elevation to feed a sheet of material.

Signed by me at Chicago, Illinois, this 12th day of September, 1916.

EDWARD CRAIG.
